UNITED STATES PATENT OFFICE.

ERNEST RICHARDSON, OF COLLEGE HILL BOROUGH, PENNSYLVANIA.

ENAMELED RADIATOR.

Application filed July 5, 1921. Serial No. 482,303.

To all whom it may concern:

Be it known that I, ERNEST RICHARDSON, a citizen of the United States, residing at College Hill Borough, Beaver County, and State of Pennsylvania, have invented new and useful Improvements in Enameled Radiators.

My invention relates to sectional radiators heated by steam, or water. The object of this invention is to provide an enameled sectional radiator on which the enamel will not be cracked or broken at the joints between the sections.

Referring to the accompanying drawing, Fig. 1, is a side elevation of a radiator containing my invention, parts being omitted and broken away; Fig. 2, an end elevation of one end of one section of said radiator; and Fig. 3, a vertical enlarged section through the upper end of two assembled sections of my radiator; Fig. 4 is a section on the line IV—IV of Fig. 2.

On the drawing, I show a metal radiator built from a number of hollow sections or units 1. These sections, except the end ones, are interchangeable. These have at opposite sides at each end a lug or boss 2 with its outer face 3 parallel with the unit bearing the same. These bosses and faces are correspondingly arranged on the units so that, when the units are assembled in a series, the faces 3 on adjacent units will be contiguous or will fit, one on the other. These faces have correspondingly located holes 4 communicating with the steam or water passages 5 in the heads 6 of the units. The holes 3 in each pair of adjoining bosses 3 contain an oppositely tapered nipple 7 which fit the said holes to prevent

the escape of fluid through the holes 4 to the faces 3 and the exterior of the radiator. The terminal units of the radiator do not have the holes 4 in the outer faces of the heads 6 as shown in Fig. 3.

The heads 6 of each section are connected by two members 8 separated by the space 9. The end units have at each end of the space 9 a perforated wing or lug 10. Bolts 11 are passed through the lugs in the terminal units and through the spaces 9 of the intermediate units for the purpose of binding the units into a larger rigid unit or radiator.

In the manufacture of each unit it is, except on the faces 3, coated with enamel and fired or burned in any suitable manner. The meeting faces 3 not having any enamel thereon, there will be no cracking or chipping of the enamel at or around the joints of the contiguous bosses 2. If enamel were on the faces 3, it would be cracked or chipped away in spots by the pressure due to the clamping action of the bolts 11 or to the action of the heat in the joints.

The enamel may be left off from the wings 10 on the parts on which a head or nut on the bolts 11 bears in order to prevent the cracking and chipping of the enamel around the nuts and bolt heads.

I claim:

A unit for assembly in a radiator having a series of said units with abutting surfaces, the unit having its exterior enameled except on a surface designed to abut against a companion surface on another unit.

Signed at Pittsburgh, Pa., this 29th day of June, 1921.

ERNEST RICHARDSON.
